CLAIM

The ornamental design for a fragrance machine as shown and described.

DESCRIPTION

FIG. 1 is a top perspective view of a fragrance machine showing my new design;

FIG. 2 is a bottom perspective view thereof;

FIG. 3 is a front plan view thereof;

FIG. 4 is a rear plan view thereof;

FIG. 5 is a left side plan view thereof;

FIG. 6 is a right side plan view thereof;

FIG. 7 is a top plan view thereof; and,

FIG. 8 is a bottom plan view thereof.

The broken lines shown in the drawings depict portions of the fragrance machine that form no part of the claimed design.
